UNITED STATES PATENT OFFICE.

THEODORE LINDENBERG, OF COLUMBUS, OHIO.

REPRODUCER FOR RADIO RECEIVING APPARATUS.

Application filed January 13, 1926. Serial No. 80,917.

The present invention is directed to an improved amplifier or reproducer for use in connection with radio receiving apparatus. The object of the invention is the provision of a reproducer embodying peculiar features of design by which the quality and volume of the emitted sounds are of a greatly improved character, as compared with the present ordinary apparatus for this purpose, and wherein not only are the basic or fundamental sounds reproduced but, in addition, the overtones and rich harmonic shadings are locally developed to enhance the tonal quality of the sound, to permit of a faithful rendition of the artist's efforts in reproduced form and to increase correspondingly the enjoyment and pleasure of the listeners.

In accordance with the invention there is provided a radio reproducer consisting of a plurality of individual reproducing units, and wherein the amplifying horns of said units have the resonant walls thereof formed from different materials possessing varying resonating properties, each of said units having the capacity of developing certain sounds to better advantage than other sounds, whereby said units operate to develop the received signal energy completely and elaborately providing a means, covering the entire range of audible sound wave frequency, for developing, for example, the characteristic sounds of various orchestral instruments, so that each individual sound may be reproduced in proper proportion to the entire volume of sound reproduced. It has been observed that a single radio reproducer or loud speaker of ordinary design does not function to develop adequately to reproduce clearly and faithfully the sounds produced by the artist. It has been noted that in loud speakers, where the same are of the horn or cone type, there is present in the reproduced sound the characteristic, peculiar mechanical properties of the reproducer. Moreover, a reproducer having a diaphragm of fixed sides and an associated amplifying horn of determined area and formed from a single material can not function to accurately reproduce the noise and sounds of, for example, various orchestral instruments. A large reproducer of wood may develop the stringed instruments of an orchestra satisfactorily but would not develop in a true phonetic way the brass or metallic instruments. Realizing, therefore,

the inherent limitations in reproducers of this kind, the present invention consists in the grouping of a number of reproducer units, each having amplifying elements of varying size and material and adapted to operate simultaneously from a single radio receiving apparatus, the arrangement being such that through the use of a plurality of such elements the reproduced sound would be properly developed throughout the entire audible range of sound frequency, resulting in the production of sound possessing strength and body with the overtones present in full degree, enabling the various individual sounds to be heard in their true relative proportions with the entire body of sound, and overcoming especially the "thinness" and mechanical limitations of the ordinary radio reproducer.

For a further understanding of the invention reference is to be had to the following description and the accompanying drawing in which:

Figure 1 is a front elevation of a radio reproducer constructed in accordance with the present invention, parts of the cabinet of said reproducer being shown in section to disclose the interior structure.

Figure 2 is a vertical cross-sectional view on the line 2-2 of Figure 1.

Figure 3 is a plan view disclosing the relative proportions of the diaphragms used in the several units of the reproducer.

Referring more particularly to the accompanying drawing the numeral 1 designates the improved reproducer comprising the present invention in its entirety. In the specific form of the invention illustrated and hereinafter described the reproducer is formed to include a cabinet 2 of any appropriate design, which is preferably formed in a cabinet such as form that of the radio receiving apparatus (not shown) with which the reproducer is associated. The cabinet includes a base 3, vertical end walls 4, a back wall 5 and a top 6. Within the cabinet there is arranged a horizontally extending wall 7, that divides the interior of a cabinet into an upper amplifying chamber 8 and a lower apparatus and battery chamber 9. The chamber 9 is closed by a front wall 10, while the amplifying chamber 8 is preferably open at its front but may be partially closed by a foraminated wall or screen 11.

Mounted upon the horizontal wall 7 of the

cabinet is a plurality of "loud speaker" or reproducer units 12. In the present instance these units have been shown as of the customary "horn" type, but it is obvious that other types of units, such as the "cone" type may be utilized. It is a very important feature in practicing the present invention to form the horn portion particularly of each unit from a different material than that constituting the horns of the remaining units. Also, another outstanding feature is the fact that the area of the diaphragms 13 as well as the amplifying horns 14 thereof vary in relation to each other. Thus, it will be seen that the horn at the reader's left in Figure 1 of the drawing is considerably smaller in area than the horn at the right, and this is true, as shown in Figure 3, in regard to the relative proportions of the diaphragms 13. The horns 14^a, may, for example, be formed from metal, the horns 14^b, from a composition material, such as wood fiber or the like, whereas the horn 14^c may be formed from grained wood or a combination of wood and metal. It will be seen that due to the varying size of materials from which the units 12 are formed each particular unit will be adapted to amplify to better advantage certain individual sounds than the remaining units, and by virtue of the assembly of these units in a single structure, the final sound produced will possess a pleasing combination of both beauty and volume not found in analogous apparatus of which I am aware.

Preferably, the units 12 are arranged so that their outlets face toward a sounding board 15 mounted for vibration within the chamber 8 of the cabinet and which reflects the sound through the screened front wall of the cabinet. It will be observed that the sounding board is more in the nature of a reflector and is of considerable utility in discharging the sound from the reproducer in such a manner that the sound will appear to emanate from the front of the reproducer rather than from a point deep in the interior thereof.

The chamber 9 of the cabinet includes in this instance an audio-amplifying unit 16, usually of the so called "push-pull" variety. The batteries for this apparatus may be placed in the chamber 9, and leads 17 extend from the output side of the amplifier to the reproducer units 12. Manually operated switches 18 are preferably arranged in connection with these leads so as to control at will the operation of each unit, namely one or more of said units to be cut off whenever desired. An in-put connection 19 is arranged at the side of the amplifying ap-

paratus 16 and with which the leads from the associated receiving set are detachably connected. It will be appreciated that any standard form of radio receiver may be utilized in connection with the reproducer and that the latter will be enabled to augment the strength of the received signal energy to an extent necessary to operate the reproducer units to their usual working power. The back of the cabinet is provided with a hinged wall 20 affording access to the interior of the chamber 9.

In view of the foregoing description, taken in connection with the accompanying drawing, it will be seen that the present invention provides a radio reproducer or loud speaker of unusual design, which possesses the capability of reproducing the electrically created sound oscillations to a degree very closely approximating the originally created sounds of the artist. There is present in the reproduced sound a vitality and body of natural strength and vigor, having a rounded and blended character wholly unusual, so far as I am aware, in apparatus of a similar nature. In forming the amplifiers of the reproducing units from different materials a very marked improvement in the emitted sound has been noticed, and this has been supplemented by the varying size of the amplifying units. The device in its commercial form may be placed in an attractively modeled cabinet either in connection with or remote from an associated radio receiving set.

What is claimed is:

1. A reproducer for radio receiving apparatus comprising a plurality of reproducing units, said units being formed to include amplifying sections, one of said sections having the walls thereof formed from wood, another section from metal and a third from a moulded composition material, and means permitting said units to be simultaneously energized.

2. In radio reproducing apparatus, a plurality of reproducing units, each of said units being formed to include an amplifying horn, the horns of said unit being formed from different materials and of varying size and proportions, a signal amplifying unit, and leads extending from said signal amplifying unit to said reproducing units for effecting simultaneous operation of the latter.

3. A structure as specified in claim 2 in connection with switches provided in said leads for controlling selectively the operation of said reproducer units.

In testimony whereof I affix my signature.

THEODORE LINDBERG.
